WATER-COLOR PAINTING KIT

Edith Fleming Crane, Poughkeepsie, N. Y.

Application April 12, 1946, Serial No. 661,534

10 Claims. (Cl. 41-5)

1

This invention is a novel water color painting kit adapted to be used with great success by teachers, artists, designers, and amateurs who wish to enjoy accomplishment in the art of painting, same including a palette the use of which will give surety of basic harmony in that it indicates harmonious combinations of color so that the basic harmonies can be readily recognized due to the position of the paints on the palette.

The objects of the invention are:

1. To provide a box for equipment which may be made of plastic paste, wood pulp, wood coated with plastic paint, or enameled wood or tin, said box to be divided into compartments designed to keep a complete painting and sketching outfit in compact form, the box having separate compartments for—

- (A) Color tubes and cloths;
- (B) Brushes, and sketching implements;
- (C) Rubber cement, erasers, scrubs, and so forth;
- (D) Thumbtacks;
- (E) A sponge;
- (F) A removable water pan, divided into two parts by a partition, one part for holding clean water, and the other for water in which to wash used brushes.

2. To provide a palette—

- (A) With color pans so arranged that color harmony readily follows in the use of the paints in order;
- (B) With ample mixing pans, including a center pan for mixing a pair of complementary colors in order to obtain a harmonious gray when using complementary harmony;
- (C) With a slight lift at the back of the palette, where the color (Y), yellow, is indicated, to give a better visibility of the paints when the palette is being used, and to enable the painter to lift the palette easily from a flat surface.

3. To provide a box lid—

- (A) To close the box and protect the paints;
- (B) Constructed with a thumb hole so that it can be turned over and held in the left hand as a mixing palette when experimenting;
- (C) To be used as a supplementary water reservoir when desired.

4. To provide a locking device—

- (A) Which attached to the right hand lower corner of the palette, extends through the thumb hole in the lid and swivels to secure the lid to the palette and the box;

2

- (B) To be used as a hand rest to steady the hand when taking paint from the palette;
- (C) To be used as a brush holder when the brush is wet with paint and should not be laid down touching a flat surface.

Other minor objects of the invention will be hereinafter set forth.

I will explain the invention with reference to the accompanying drawings, which illustrate two practical embodiments thereof, to enable would-be artists and amateurs to learn readily the art of water color painting, and to give teachers a modern, simplified method of teaching color; also, I will summarize in the claims the novel features of construction, and novel combinations of parts, for which protection is desired.

In said drawings:

Figure 1 is a top plan view of my novel kit, showing the locking device in locking position, a portion of the lid being broken away to show the underlying palette.

Fig. 2 is a side elevation of the kit shown in Fig. 1.

Fig. 3 is an enlarged vertical section on the line 3—3, Fig. 1.

Fig. 4 is a plan view of the box of the kit, detached.

Fig. 5 is a transverse vertical section on the line 5—5, Fig. 1.

Fig. 6 is a plan view of the locking device in position to permit removal of the lid from the kit.

Fig. 7 is a view similar to Fig. 6, showing the locking device in position to hold the lid on the palette and in place to be used as a hand or brush rest if the lid were removed.

As shown, my novel kit comprises a box 1 of general rectangular plan, preferably square, to hold a square palette and closed at its bottom 1a. (Figs. 2 and 5), while being open at the top, the said top being higher at one side than at the opposite side, and the top edges of the remaining sides slanting downwardly, as at 1b (Figs. 2 and 5) for the purpose hereinafter set forth.

Within the lower portion of the box 1, are a plurality of partitions 1c (Figs. 2 and 4) arranged at right angles to each other and extending upwardly from the bottom, and terminating below the upper edge of the box 1, said partitions all being of the same height and being arranged to provide a large compartment A (Fig. 4) adapted to hold paint tubes and a paint cloth, a parallel compartment B, adapted to hold brushes, pencils and charcoal, a short compartment C, adapted to hold erasers, scrubs, rubber

cement or the like, and two smaller compartments D and E, the compartment D being adapted to hold thumbtacks, while the other compartment E is adapted to hold a sponge; also a larger compartment F, adapted to hold a pan G, having a partition G' dividing the pan G into substantially equal compartments, one for holding clean water and the other for holding water for washing the brushes, the pan G preferably being a single pan having a central partition G'; however, two separate pans may be utilized if desired in compartment F.

The box 1 above described may be made of plastic, pressed wood, coated with plastic paint or enameled wood, or tin or other light material.

In connection with the box 1, I provide a palette 2 shown more particularly in Figs. 1 and 5, same being preferably formed of plastic, or pressed wood being coated with plastic paint, the same being square and of slightly less area than the box 1, so that it may fit within the box 1, as shown in Fig. 5. Palette 2 is of thickness equal to the portion of the high side of the box above the tops of the partitions 1c, but enough less to allow the covering lid to be flush with the top of the box front at 1d (Fig. 5) and as indicated in Fig. 2.

The palette 2, as indicated in Fig. 1, is provided with a central depression 2a, and an annular series of circular depressions 2b, labelled with raised letters indicating colors, concentric with the depression 2a, the series containing 12 such depressions arranged as shown in Fig. 1. Between each of the depressions 2b and the central depression is an annular series of twelve substantially triangular depressions 2c.

As shown, the bottom of each of the depressions 2a and series of twelve depressions 2b is semi-spherical, so they can be easily cleaned. The bottom of each of the triangular depressions 2b, as shown, slopes downwardly and outwardly from the center of the palette without any sharp angles at the bottoms of the depressions so paint can be wiped out easily.

At the rear end of the palette 2, adjacent the rear corners thereof are two further depressions 2d, serving as extra receptacles for black, and white, and/or gold and silver.

Along the rear bottom edge of the palette 2 is a shoulder or lift 2e, adapted to tilt the palette forward when removed from the box, and placed on a flat support. The base of the lift may be slightly beveled so that it will lie evenly against a flat surface.

As indicated in Fig. 1, the triangular depressions 2b are lettered to hold water color paints arranged in a circular spectrum for color harmony, for instance, colors arranged in a clockwise direction as indicated in Fig. 1, beginning at the back center or top of the color wheel, are as follows: (Y) yellow; (Y-G) yellow-green; (G) green; (G-B) green-blue; (B) blue; (B-V) blue-violet; (V) violet; (R-V) red-violet; (R) red; (R-O) red-orange; (O) orange; (Y-O) yellow-orange. By such a disposition the paints are so arranged that opposite colors are complementary and analogous colors are adjacent. The central depression 2a is to be used to secure a neutral gray to harmonize with complementary colors, and the depressions 2c are adapted for use as mixing pans or to hold extra desired commercial colors.

In connection with the kit, I provide a lid 3 of same area as the palette 2 and adapted to overlie the same and extend half-way down the

palette back to close the box, the lid also having inclined sides 3a (Figs. 2 and 5) adapted to conform with the inclined top edges 1b of the box 1, so that when the palette and lid are assembled on the box 1 the lid will completely close the sides, back, and top thereof. The lid 3 is preferably made of the same material as the box 1, and/or the palette 2.

In the front right corner of lid 3 is an oval-shaped thumb opening 3b, with its short axis if extended bisecting the lid from upper left hand corner to lower right, as clearly indicated in Fig. 1, said opening 3b forming a thumb opening whereby the lid when removed from the box may be inverted and used as an additional water pan, the lid if tilted holding water by reason of the inclined sides 3a and the apron back. The thumb opening 3b is provided with recesses 3c, at the ends of its long axis, as indicated in Figs. 1, 6, 15 and 7, for the passage therethrough of a locking member 4, which consists of a substantially U-shaped rotatable strip having a pivot 4a and having one leg 4b longer than the other leg 4c, as clearly indicated in Figs. 1, 3, and 7.

Pivot 4a registers with a bore 2x, Fig. 2, in the palette 2 underlying the lid 3, which bore 2x is offset from a point in the thumb hole 3b, so that a pivot pin 5, passing through the bores 2x and through the pivot opening 4a would just allow the locking device to pass through the extensions in the thumb holes 3c and 3e; the pivot to have its ends riveted or otherwise enlarged so that the locking member 4 may swivel on the pin 5, but cannot become disconnected therefrom, the locking device 4 being loosely swiveled on pin 5. The end of pin 5 is recessed up in the palette so no projection will tip the palette.

By the above construction, the locking device 4 is permanently secured to the palette 2 and serves not only as a locking device for the cover 3 but also serves as a hand rest on the palette 2, and as a brush holder since the ferrules of the brush may be supported in the central depression of the locking member adjacent the pivot 4a to keep the brush from rolling off of the palette and dabbing surrounding surfaces. And, as shown in Fig. 6, when the locking device 4 is positioned in alignment with the opposed recesses 3c of the thumb hole 3b, the lid may be readily lifted off of the top of the palette and off box 1.

As some persons might not desire to use the locking device as a hand or brush rest, the end 5, instead of being riveted, could be finished so the locking device could be removed easily from the palette, i. e., the end of the rod could be threaded and a small threaded ring or nut screwed over the end to hold it. Other removable means could be used also.

When swung into position shown in Fig. 7, the locking device 4 will prevent the lid 3 from being removed from the palette 2.

By the above indicated position of the locking device and thumb hole, the said thumb hole 3b cannot expose the underlying pans or depressions in the palette 2, and thus the paint in the depressions 2b will not be exposed through the thumb hole 3b. The lid 3 protects the paints and makes a complete box when the palette 2 is in the box; and the lid 3 may be fastened by the locking device 4 against the palette 2 alone when in the position shown in Fig. 7, or when the palette is in the box it can be turned so that the long arm 4b also catches or bears against the adjacent top edge of the box 1. The lid also will prevent the paint from being exposed to dust during periods

5 when the kit is not in use, thus preventing premature deterioration of the same.

My invention provides a novel, useful and efficient means in which the colored paints in the palette 2 are arranged in labeled depressions in the order of the teaching device generally referred to as a color wheel, the paints being so placed in the depressions in the palette that opposite colors are complementary, and analogous colors are arranged adjacent. The triads also may be readily recognized. In using the paints on my palette in any of the orders indicated, one is sure to have correct color balance or harmony in the design or picture. For convenience, the palette may be lifted from the box in which the equipment is kept, and used separately, the box being merely for storing needed material and for carrying the palette and equipment from place to place out of doors.

An explanation of the use of my color palette in securing harmony and balance of all color, is as follows:

According to my invention the color pigments are arranged and lettered in the color depressions 2b of palette 2 in the order for teaching, called a "color wheel." This arrangement places the paints so that opposite colors are complementary while analogous colors are disposed adjacent; the triads are also easily recognizable. In using the paints in any of the orders indicated, one is sure to have correct color balance or harmony in the design or picture.

MINGLING

Color harmony is the balance of all color. In working with any of the harmonies, it is advisable to make a mingling of the paints, in the harmony desired, which can be used as the basis for painting the actual design. In order to make said mingling, wet a piece of paper the same as that to be used for the finished painting and drop the chosen colors on the wet paper. Then turn the paper in the hand to guide the mingling of the paint. All hues resulting from this mingling will be harmonious. Mingling paints in this manner gives the best quality of color, and muddied effects due to mixing are avoided. If the painter desires a greater percentage of one color than another, the mingling can indicate such choices, and the paints can be used to obtain the particular hue that is most pleasing. In order to obtain balance of color and pleasing effects use the paints in the four harmony orders, to wit, (1) complementary; (2) near-complementary; (3) analogous harmony; and (4) the triads.

COMPLEMENTARY HARMONY

(1) For complementary harmony, use any set of two opposite colors in the palette 2, color pans 2b such as yellow (Y), and violet (V). Mix in equal amounts in center pan 2a to obtain a neutral gray which harmonizes with said two colors. Either color may be slightly toned for shadow by using a small amount of the other. There are 65 six pairs of complements on the palette 2.

NEAR-COMPLEMENTS

(2) For harmony of the near-complements, select a color and combine same with either one of the two colors adjacent to its complement, such as yellow (Y), with red violet (R-V) or blue violet (B-V), the colors on either side of violet (V) which is the complement of yellow. There are 70 twelve combinations of near-complements on the

palette 2 as each color can be combined with either of two near-complements.

ANALOGOUS HARMONY

5 (3) For analogous harmony, use colors which are adjacent on palette 2 on which the colors of the rainbow are arranged in a circle. Use any two, three, or four colors around the palette for analogous harmony. For brilliance use four colors and one of the complements of the inner pair for shadow, such as red-orange (R-O), orange (O), yellow-orange (Y-O), and yellow (Y), the adjacent colors in pans 2b and the complement of orange, blue (B), or the complement of yellow-orange, which is blue-violet (B-V). As one could choose to commence with any of the twelve colors, there are twelve such combinations of analogous harmonies provided for on the palette 2.

(a) In order to paint flowers of any color use analogous harmony for colors representing sunshine striking a petal to denote the hue modified by the light, and also the hue modified by shadow. So, as in painting a red flower some petals will appear yellow-orange, or orange, at least red-orange where the light strikes the petals, and though the flower will be generally red, the shadows will shimmer from red-violet to violet.

(b) In order to paint round objects the swing of analogous harmony will be from the highlight on the object to the deepest hue and back again to the hue of the highlight for the reflected light underneath. The paint should be put down in elliptical zones, and five adjacent hues on the palette from the pans 2b used. The shadow cast by the object should be modified by the complement of the main hue.

(c) In order to paint pictures of the same landscape showing the atmospheric changes of the times of day use the following combinations for the different hours—

Daylight hours, brighter or left side of palette

45 6 a. m., Y, Y-G, G, B-G plus R.
8 a. m., Y-O, Y, Y-G, G plus R-V.
10 a. m., O, Y-O, Y, Y-G plus V.
12 n., R-O, O, Y-O, Y plus B-V.
2 p. m., R, R-O, O, Y-O, plus B.
4 p. m., R-V, R, R-O, O plus B-G.
6 p. m., V, R-V, R, R-O plus G.

Night, darker or right side of palette

50 8 p. m., B-V, V, R-V, R plus Y-G.
10 p. m., B, B-V, V, R-V plus Y.
55 12 midnight, B-G, B, B-V, V plus Y-O.
2 a. m., G, B-G, B, B-V plus O.
4 a. m., Y-G, G, B-G, B plus R-O.

Length and direction of shadows

60 60 Shadows at 6 a. m. will be long shadows falling from the direction of the rising sun. They will grow shorter and swing from west to northwest until there are none when the sun is directly overhead, when they will be back of or under objects. At noon the swing in the opposite direction begins from north northeast to northeast, the shadows growing longer until they reach the longest when extending toward the east at the setting of the sun. The shadow of an object of any hue on the palette would be represented, or painted, by using the color opposite on the palette, as an object of the general hue of yellow (Y) would cast a shadow of its complementary hue, violet (V), and the shadow would be greyed as desired by mingling yellow with its complement, violet.

TRIADS

(4) The triads are combinations of three harmonizing colors. The colors of the triads are spaced three colors apart around the palette no matter with which color you begin to select a triad. There are four triads on the palette 2, to wit:

- A. Red, yellow, and blue (the first triad).
- B. Orange, green and violet (the second triad).
- C. Yellow-orange, blue-green and red-violet.
- D. Red-orange, yellow-green and blue-violet.

To locate a triad on the palette 2, choose any color in a pan 2b as the apex of a triangle with equal sides—the three colors will give color balance.

Each triad will give a truly balanced set of values, but the third and fourth are different, less vivid.

In order to paint landscapes in season use the following combinations:

- Summer—red, yellow, and blue.
- Autumn—orange, green, and violet.
- Winter—yellow-orange, blue-green, and red-violet.
- Spring—red-orange, yellow-green, and blue-violet.

For portrait painting, the following triads have been used successfully by many artists:

- Blonds—Yellow-orange, blue-green, red-violet.
- Dress, blue-greens; Background, red-violet.
- Brunettes—Red-orange, yellow-green, blue-violet.
- Dress, red-orange with background, yellow-green; or dress, yellow-green with background, red-orange.

I do not limit my invention to the exact form shown in the drawings, for obviously changes may be made therein within the scope of the claims.

I claim:

1. A water color painting kit, comprising a rectangular box open at the top; partitions within the box terminating below the top thereof; a removable palette within the upper portion of the box seating upon the tops of the partitions; a locking bar swiveled at one corner of the palette; and a removable lid closing the top of the box and overlying the palette, said lid having a diagonally disposed slot therein in way of the locking bar through which the locking bar is adapted to pass when in one swiveled position.

2. In a kit as set forth in claim 1, said box having its front edge substantially flush with the top of the lid when positioned thereon and its back edge terminating substantially half the height of the palette when inserted therein, the side edges of the box sloping at an angle between said front and back edges; and the lid having complementary shaped sides and back adapted to completely close the sides and back of the box when positioned thereon with the palette housed therein; and said locking bar and slot in the cover being disposed at the right hand corner of the front edge of the box.

3. In a kit as set forth in claim 1, said palette being of slightly less area than the box, and having a centrally disposed depression, and having an outer annular series of depressions disposed coaxially thereof adjacent the periphery of the palette, and having an inner annular series of further depressions intermediate the central and outer series; said palette having a pair of still further depressions adjacent the rear corners of the palette; indicia arranged in a circular spec-

trum for color harmony opposite the outer annular series respectively, with the indicia denoting the color yellow disposed opposite a depression of the circular series midway between the last mentioned pair of depressions.

4. In a kit as set forth in claim 1, said palette being of slightly less area than the box, and having a centrally disposed depression, and having an outer annular series of depressions disposed coaxially thereof adjacent the periphery of the palette, and having an inner annular series of further depressions intermediate the central and outer series; said palette having a pair of still further depressions adjacent the rear corners of the palette; indicia arranged in a circular spectrum for color harmony opposite the outer annular series respectively, with the indicia denoting the color yellow disposed opposite a depression of the circular series midway between the last mentioned pair of depressions, said locking device being disposed at the right front corner of the palette; and a tilting rib on the underside of the palette along the back edge thereof.
5. In a kit as set forth in claim 1, said slot forming a thumb hole when the lid is removed and held inverted for use as a supplemental mixing palette, the sides and back of the cover serving as a supplemental water reservoir when so held.

- 30 6. A water color painting kit, comprising a square box open at the top; partitions within the box terminating below the top thereof; a square removable palette within the upper portion of the box seating upon the tops of the partitions; 35 a locking bar swiveled intermediate its ends at one corner of the palette; and a removable lid closing the sides and back of the box and overlying the palette, said lid having a diagonally disposed slot therein in way of the locking bar 40 through which the locking bar is adapted to pass when in one swiveled position.

7. In a painting kit, a rectangular box open at the top; partitions within the box terminating below the top thereof; a removable palette within the upper portion of the box seating upon the tops of the partitions; a removable lid closing the top of the box and overlying the palette; said box having its front edge substantially flush with the top of the lid when positioned thereon and its back edge terminating substantially half the height of the palette when inserted therein, the side edges of the box sloping at an angle between said front and back edges; and the lid having complementary shaped sides and back adapted to completely close the sides and back of the box when positioned thereon with the palette housed therein.

8. In a kit as set forth in claim 7, said lid having a slot therein forming a thumb hole when the lid is removed and held inverted for use as a supplemental mixing palette, the sides and back of the cover serving as a supplemental water reservoir when so held.

9. In a color painting kit, a square palette having a centrally disposed depression, and having an outer annular series of twelve other depressions disposed coaxially thereof adjacent the periphery of the palette, and having an inner annular series of further depressions intermediate the central and outer series; said palette having a pair of still further depressions adjacent the rear corners of the palette; indicia arranged in a circular spectrum for color harmony opposite the outer annular series respectively, with the indicia denoting the color yellow disposed oppo-

site a depression of the annular series midway between the last mentioned pair of depressions.

10. In a color painting kit, a square palette having a centrally disposed depression, and having an outer annular series of twelve other depressions disposed coaxially thereof adjacent the periphery of the palette, and having an inner annular series of further depressions intermediate the central and outer series; said palette having a pair of still further depressions adjacent the rear corners of the palette; indicia arranged in a circular spectrum for color harmony opposite the outer annular series respectively with the indicia denoting the color yellow disposed opposite a depression of the annular series midway between the last mentioned pair of depressions; a pivoted locking bar disposed at the front

right corner of the palette; and a tilting rib on the underside of the palette along the rear edge.
